WILLIAM HENRY, OF NEW BEDFORD, MASSACHUSETTS, ASSIGNOR TO STODDARD, HASERICK, RICHARDS & COMPANY, OF BOSTON, MASSACHUSETTS, A FIRM.

STOP-MOTION ESPECIALLY ADAPTED FOR COMBING-MACHINES.

No. 824,787.

Specification of Letters Patent.

Patented July 3, 1906.

Application filed April 13, 1905. Serial No. 255,419.

To all whom it may concern:

Be it known that I, WILLIAM HENRY, a citizen of the United States, residing at New Bedford, in the county of Bristol and State of Massachusetts, have invented a new and useful Improvement in Stop-Motions Especially Adapted for Combing-Machines, of which the following is a specification.

Combining-machines, as is well known, act upon the lap, which in the combing well known as the "Heilman" combing is fed down the incline conductor and between the fluted and pressure rolls to the nippers. During the ordinary operation of the machine the lap or sliver often breaks between the rolls and the nippers and winds on the fluted roll. Its increasing thickness crowds the cushion-plate against the needles of the half-lap or breaks the nippers-stand, so that the machine must be stopped and the lap cut off before the machine is in condition to start up again. The sooner the machine is stopped after the winding begins the less time is wasted in cutting off the lap and readjusting the machine for continuing its work; but as the operator may have charge of several of these machines it often happens that there is considerable delay, due to the fact that he may be attending to one machine while an accident of this kind may happen on the next. My invention is intended to remedy this difficulty by providing a stop-motion which is brought into action by the gradual thickening of the lap as it winds upon the fluted roll. As the layers increase the fluted roll tends to bind, so that it requires an increased power to rotate it, and in the form of my invention hereinafter described I utilize the increase of resistance of the roll to cause such an operation of the belt-shipper as will throw the belt from the fast to the loose pulley on the power-shaft.

My invention will be understood by reference to the drawings, in which—

Figure 1 is a sectional view of the essential parts of the well-known "Heilman" combing, to which I have applied my invention, Figs. 2 and 3 being details illustrating my invention. Fig. 4 is a sectional view on line 4-4 of Fig. 3, taken in the direction of the arrow.

I will not describe the combing in detail further than to say that A is the lap wound on the usual core and resting on the wooden

rolls B. The lap passes down the inclined conductor C and between the lower or fluted roll D and the pressure-roll E and within reach of the nippers e. These parts are suitably supported in the frame A' and are of ordinary construction and are operated in the ordinary way except as hereinafter described. The fluted roll D is mounted on or is virtually a part of the shaft d, and, as usual, a number of laps are operated on by a corresponding number of fluted rolls and the other accessories of the combing. This shaft d may combine a number of these fluted rolls, all operated from the same power-shaft.

The power-shaft is lettered G and carries the usual fast and loose pulleys G' G², G³ being a belt by which they are connected with the shafting or other source of power and which may be thrown from one pulley to the other by a belt-shipper G⁴. The belt-shipper G⁴ is of ordinary construction, being pivoted at g and carrying a belt-engaging loop g', and it is operated by a curved rod G⁵, pivoted to it at g² and running in bearings G⁶. This rod G⁵ has a coiled spring G⁷ about it, one end of which rests against an arm G⁸, connected with the bearings G⁶, while the other end rests against a collar G⁹, adjustable on the rod G⁵. This construction is such that the tendency of the spring G⁷ when compressed is to throw the belt from the fast to the loose pulley. This action, however, is normally prevented by means of a latch, one member of which, H, is mounted on the collar G⁹ and the other a notched lever H', pivoted at h on the arm G⁸. The notch on the lever H' is so located that when the parts are in the position shown in Fig. 2 it will engage with the latch member H and so confine the spring G⁷ that it cannot throw the belt-shipper and the belt from the fast to the loose pulley. When, however, the lever H' has been lifted to disengage it from the other latch member H, the spring G⁷ then on expanding throws the belt-shipper, and hence the belt, from the fast to the loose pulley. As described, this may be done by hand; but my invention more especially relates to the accomplishing of this operation automatically at such time as the winding of the lap on the fluted roll has taken place. I have not shown the connections between the power-shaft G and the shaft J, by means of

which power is more immediately transmitted to the shaft d , carrying the fluted roll D , as those connections are common. I will only say that the shaft J carries a pinion j , which engages with a gear J' on and concentric with the axis of the shaft d . The shaft d is connected with the gear J' by a yielding connection, by means of which while the gear J' may be rotated at a constant rate of speed any increased friction on the shaft d will prevent its rotation with the gear J' to a greater or less extent, and it is the utilization of this possible difference of rotation between the fluted roll and the gear carried by it and by means of which it is rotated which enables me to accomplish the desired result and which embodies my invention in its best form.

As shown in the drawings, the shaft d carries a sleeve d' , keyed thereto, and having an arm d^2 projecting therefrom parallel with the face of the gear J' . This arm has a stop-lever d^3 pinned to it at d^4 , which stop-lever is also pinned to the gear J' by the pin j' . I prefer that the gear J' shall be mounted free to turn upon a sleeve d' . A spring (comprising, as shown, in fact, two springs, the one, d^6 , being in the nature of a lever pinned to the gear J' at d^7 and the other, d^8 , also attached to the gear J' at d^9 and to the spring d^8 as well) engages a pin d^{10} on the stop-lever d^3 . These springs are of such strength that under all the ordinary conditions of operation they hold the shaft d and the gear J' firmly together. When, however, any unusual strain or friction is applied to the shaft d —such, for example, as might be caused by the winding up of the lap above referred to—the arm d^2 and gear J' cease to move in unison, the arm d^2 hanging back, and consequently by reason of the binding of the stop-lever d^3 causing the stop-lever against the force of the spring acting upon it to be thrown forward into the position shown in dotted lines in Fig. 2 until it strikes the pin d^{11} . This action of the stop-lever brings it within reach of an arm h' , adjustably carried by the rod h^2 , which is connected to the latch-arm H' , its lower end running in an opening in a bracket h^3 , attached to the gear-case h^4 . As the toe of the stop-lever d^2 strikes the arm h' it lifts it, thus lifting the latch-lever H' and releasing the spring G' , so that the belt-shifter is thrown from the fast pulley to the loose pulley and the machine is disconnected from the power-shaft, thus stopping the machine.

While it is evident that this means of throwing the belt-shifter may be accomplished by means of other mechanical details, I believe that I am the first to utilize the friction or increasing resistance of the fluted roll to cause the operation of the belt-shifter.

It is also evident to those skilled in the art

that while I have specifically described this invention in connection with the lower roll in a combing-machine its peculiarities are adaptable to other machines of a similar nature where the lower roll is inclined to wind up any broken lap or sliver which is passing between it and the upper roll. Therefore I do not mean to limit my claim to a mechanism of this character when used on a combing-machine nor, in fact, to a bottom roll, for it is applicable to any roll upon which a sliver is liable to wind.

What I claim as my invention is—

1. In a machine of the character described, having an upper and a lower roll, means for operating said lower roll yieldingly connected therewith and capable of engagement with a stop-motion for said machine, whereby when the said lower roll and its operating means are running at separate rates of speed, said operating means will operate said stop-motion, as described.

2. In a machine of the character described, a lower roll, a gear yieldingly connected therewith, means for applying power to said gear and said lower roll, means carried by said gear adapted to disconnect said gear from the source of power when said gear and said lower roll do not move in unison.

3. In a machine of the character described, a shaft carrying one or more rolls and having an arm mounted thereon to rotate therewith, a gear carried by said shaft and having an independent movement with relation thereto, a spring connection between said shaft and said gear adapted to cause said gear and said shaft to operate normally in unison, a stop-lever connected with said gear and said arm, and a stop mechanism, said stop-lever being adapted to be operated to engage said stop mechanism when said arm and said gear do not operate in unison.

4. In a machine of the character described, in combination with a pair of rolls, said rolls being separable from each other, means adapted to be operated by the separation of said rolls, whereby the said machine will be stopped, comprising a belt-shifter, a sliding rod connected thereto, a spring mounted on said rod, a latch, means for securing one member of said latch upon said slide-rod, said means also serving as means for confining said spring, the other member of said latch being mounted upon the frame, and connecting means whereby the separation of said rolls will cause the separation of the members of said latch, the release of the spring and the shifting of the belt, as described.

WILLIAM HENRY.

In presence of—

HENRY DENOYERS,
HUGH WILLIAMS.
